UNITED STATES PATENT OFFICE.

EDWARD F. McCABE, OF MAPLEWOOD, NEW JERSEY.

CONVEYING SYSTEM.

1,393,386.

Specification of Letters Patent. Patented Oct. 11, 1921.

Application filed April 11, 1918. Serial No. 227,954.

To all whom it may concern:

Be it known that I, EDWARD F. McCABE, a citizen of the United States, and a resident of Maplewood, in the county of Essex and 5 State of New Jersey, have invented new and useful Improvements in Conveying Systems, of which the following is a specification.

This invention relates to ash conveying systems and has particular reference to that 10 class of systems known as the vacuum type employed in conveying ashes from furnaces to a desired distance and remote point.

An important object of the invention is to provide in a system of the above mentioned 15 character a means whereby a sufficient partial vacuum may be created to facilitate the conveying of ashes from a boiler room to a desired and remote location regardless of any departure from a direct line of travel 20 which may be deemed necessary or advisable to make in the installation of my system.

A further object of the invention is to provide in a system of the above mentioned 25 character a means whereby the removal of ashes from any desired series of furnaces, with which my system is connected, may be either established or discontinued as desired.

A further object of the invention is to provide in a system of the above mentioned 30 character a means whereby certain elements employed therein which are subjected to excessive wear may be readily removed or disassociated from the system as a whole in order to permit these elements upon becoming 35 worn or deteriorated from constant use to be easily replaced.

A further object of the invention is to provide in a system of the above mentioned 40 character a means whereby the several elements employed therein may be subjected to the least possible amount of wear in the operation of the system as a whole thereby rendering the system more reliable in its operation than would otherwise be possible.

45 A further object of the invention is to provide a system of the above mentioned character which consists of the least possible number of elements, which is effective in use and reliable in operation.

50 Other objects and advantages will be apparent during the course of the following description.

In the accompanying drawings, forming a part of this specification and in which like

numerals designate like parts throughout the 55 same,

Figure 1 is a diagrammatic view showing the system embodying my invention, certain elements employed therein being shown in elevation and other elements in section, 60

Fig. 2 is a side elevation of a portion of a conduit, a portion thereof being broken away showing a detachable hopper installed thereupon,

Fig. 3 is an end elevation of the same, 65

Fig. 4 is a vertical transverse sectional view of a closure,

Fig. 5 is a top plan view of a hopper showing the same attached to a section of a conduit, 70

Fig. 6 is a side elevation of a conduit coupling showing a slide valve associated therewith,

Fig. 7 is an end elevation of a conduit section showing in detail a slide valve structure, 75

Fig. 8 is a perspective view of a spacing element, and,

Fig. 9 is a perspective view of an abutment, 80

In the drawing, wherein for the purpose of illustration is shown a preferred form of my invention, the numeral 10 indicates the wall of an engine room having arranged therein a plurality of boilers, two of which 85 are indicated by the numerals 11 and 12. In proximity to each of the boilers 11 and 12 there is arranged respectively, the receptacles 13 and 14 adapted to receive there- in ashes from the fire boxes of the boilers, 90

which ashes is indicated by the numeral 15. In proximity to the receptacles 13 and 14 there is disposed a conduit 16 having communication with the interior of the receptacles 13 and 14 as will hereinafter be described in detail. One end of the conduit 16 is provided with a flange 17 having connection with a flange 18 carried by a joint indicated as a whole by the numeral 19. This joint if so desired may be of the Y 100 type as clearly shown in Fig. 1, to which a conduit 20 similar to that indicated by the numeral 16 may be secured by means of a jointure as shown at 21. Between the flanges 17 and 18 there is arranged a pair 105 of segmental blocks 22 having their inner faces 23 arranged parallel with respect to each other, the space between these faces

being preferably slightly greater than the inner diameter of the conduit 16. Within the space formed between the blocks 22 there is arranged a slideable valve 24 having one end curved to conform to the contour of an abutment 25 arranged between the blocks 22 and secured between the flanges 17 and 18 as shown. The flanges 17 and 18 are secured together by means of bolts 26 which serve also as a means for retaining the abutment 25, together with the blocks 22, in position between the flanges 17 and 18. It will be seen therefore, that by this construction I am enabled not only to securely fasten the conduit 16 to the Y joint but I am enabled also to provide a simple and effective means for either severing or establishing communication between the conduit 16 and the Y joint 19 by the insertion or removal of the valve 24 as will be readily understood when considering Figs. 6 and 7. It might be well for me to state here that the jointure 21 connecting the Y joint 19 with the conduit 20 is identical with that shown in Figs. 6 and 7 and hereinbefore described and that communication is either severed or established between the Y jointure 19 and the conduit 20 in the same manner that communication is established between the conduit 16 and the Y joint 19. To the upper end of the Y joint 19 there is secured a conduit 27 which extends upwardly an appreciable distance as clearly shown in Fig. 1. To the upper end of the conduit 27 there is connected an elbow 28, which elbow in turn is connected to a conduit 29 having communication with a tank 30 supported by a suitable frame work 31. The tank 30 it will be noted is at its lower end tapered as shown at 32, this tapered end being closed or opened by manually operated valves as shown at 33. The upper end of the tank 30 is provided with a cover 34 having an opening 35 arranged centrally therein. Upon the cover 34 there is disposed a T coupling 36 communicating with the interior of the tank 30 through the opening 35. This T coupling is provided at one side with a nipple 37 serving as an inspection port, the nipple 37 being provided with a detachable closure 38. Upon the coupling 36 there is arranged a reduction joint 39, the smallest diameter of which is substantially smaller than the diameter of the coupling 36. Upon the reduction joint 39 there is arranged a silencer 40 to which is secured a water supply pipe 40' having communication with a suitable water supply not shown. Upon the silencer 40 there is imposed an exhaust pipe 41 adapted to convey the steam and air to any desired location. To the T joint there is connected a steam pipe 42 which is adapted for connection with a suitable supply of steam pressure not shown. It will be noted that the

steam pipe 42 projects a substantial distance into the T coupling 36 and is provided therein with a steam jet or nozzle 43 adapted to direct steam upwardly through the reduction joint 39, the silencer 40 and the exhaust pipe 41 in the direction of the axis common to these last named elements. The conduit 16 adjacent each of the receptacles 13 and 14 is provided with an opening 44 adapted to receive therein the base 45 of a hopper indicated as a whole by the numeral 46. The base 45 is provided on each side thereof with an ear 47 through which the ends of an arcuate shape bolt 48 is adapted to be passed, the bolt 48 serving as a means for retaining the hopper 46 in correct position within the opening 44 provided by the conduit 16. The hopper 46 carries a diverging wall 48 provided at the upper edge thereof with a flange 49. Within the wall 48 there is arranged a detachable lining 50 having its lower edge supported by a shoulder 51. This lining 50 is held in position within the hopper 46 by means of screws 52. I desire to machine the inner face of the lining 50 in order that an air-tight seal may be established between the flange 53 carried by a closure indicated as a whole by the numeral 54, the closure 54 being adapted for insertion into the hopper 46 as will be readily understood when considering Figs. 2, 3 and 4. This closure 54 is provided with a depression 55 having a hand-grip 56 arranged therein in order that the closure as a whole may be easily removed from within the hopper 46 when so desired. The lower portion of the closure 54 is provided with a depression 57 having the same curvature as the inner wall of the conduit 16. Of course it will be understood that the conduit 20 is adapted to carry hoppers identical with those indicated by the numeral 46 which are in turn maintained in communication with receptacles identical with those indicated by the numerals 13 and 14, which receptacles may be arranged for the reception of ashes from the fire boxes or boilers identical with those indicated by the numerals 11 and 12.

In use, the operation of the device is as follows: Assuming that communication is severed between the Y joint 19 and the conduit 20 and that communication between the conduit 16 and the Y coupling 19 is established and that steam is being injected into the T coupling 36 through the nozzle 43 carried by the steam supply pipe 42, a partial vacuum will be created within the tank 30, and because of this partial vacuum, ashes indicated by the numeral 15 carried within the receptacles 13 and 14, will be drawn into the conduit 16 through the hoppers 46 assuming, of course, that the closures 54 are removed from the hoppers 46. As a result of this partial vacuum the ashes 130

drawn into the conduit 16 will be conveyed through the same into the Y coupling 19 onwardly into the conduit 27 and then into the tank 30 through the coupling 28 and conduit 29 whereupon they will be deposited downward into the tank 30. As a result of the passing of the steam through the reduction joint 39 an undesirable noise is produced and for this reason I wish to employ 10 a silencer 40 to which is supplied a suitable stream of water through the water supply pipe 40'. Should it be desired to discontinue the use of either of the receptacles 13 or 14 the closure 54 may be inserted into 15 the hopper connected with the receptacle, the use of which is desired to be discontinued.

Should it be desired to discontinue the use of the conduit 16 the valve 24 may be 20 moved to the position clearly shown in Fig. 7, thereby severing communication between the conduits 16 and 27. Should it be desired to establish communication between the conduits 20 and 27 the valve 24 carried by the jointure 21 may be partially removed from between the blocks 22 whereupon ashes may be drawn into the conduit 20 from a series of hoppers identical with those indicated by the numerals 13 and 14

and connected to the conduit 20 in the same 30 manner as described in connection with conduit 16.

It is to be understood that the form of my invention herewith shown and described is to be taken as a preferred example of the 35 same, and that various changes in the shape, size and arrangement of parts may be resorted to without departing from the spirit of the invention or the scope of the subjoined claim.

Having thus described my invention, what I claim as new and desire to secure and protect by Letters Patent of the United States, is:

In an apparatus of the character described, a conduit having communication with an ash pit, an ash receiving receptacle having the bottom thereof normally closed, a nozzle supported on the receptacle and having communication therewith, a steam 45 conducting jet disposed within the nozzle and extended toward the outer end thereof, whereupon steam passing therethrough and exhausting from the nozzle a vacuum will be created in the receptacle to carry the 50 ashes through the conduit and into the receptacle.

EDWARD F. McCABE.
